SELF-SUPPORTING BAG FOR GOLF-STICKS
AND OTHER STICK-LIKE ARTICLES

Henry Theophilus Johnson, deceased; late of Putney, England, by Henry Arthur Johnson, Putney, and Ethel Mary Perring, Richmond, England, executors

Application February 24, 1933, Serial No. 658,402
In Great Britain February 29, 1932

2 Claims. (Cl. 150—1.5)

The present invention relates to improvements in and relating to golf-bags and receptacles for stick-like articles and comprehends certain improvements in or modifications of the invention 5 the subject of the prior Letters Patent No. 1,826,216.

In the specification of the aforesaid Letters Patent a spiking device is described by which the bag could be spiked into upright supporting relationship with the ground; the spike normally being retracted in a sheath or casing within the bag and being operated by a hand grip providing a divider across the mouth of the bag, such device being embodied in the bag in the original 15 manufacture thereof or more particularly being adapted for practically universal application to existing bags.

It is an aim of the present improvements so to simplify or modify the construction of the device 20 as to enable it to be applied with the greatest ease to all kinds of existing bags, without the complication of multiple additional components or loose parts which besides adding to the cost of manufacture are generally objectionable as being troublesome to assemble and liable to work loose 25 during the usage of the bag.

One feature of these improvements which is especially applicable to longitudinally stiffened bags, and is particularly intended for adapting the 30 spiking device to existing bags, consists in the provision of a member, preferably a flexible strap, adapted to be secured across the mouth of the bag to provide a club separator or separators and to serve as or co-operate in forming guiding or 35 steady means for the upper end of the spiking rod.

A further feature of these improvements consists in adapting the spiking device to stiffened or stayed bags of the type already provided with 40 a club divider or separator, such as a flexible strap or straps or other flexible or rigid division across the mouth of the bag or extending wholly or partially down the inside of the bag, and to this end is provided a guiding or steady member 45 for the upper end of the spiking rod, such guide member being attachable to the divider or separator and when attached serving to guide and steady the upper end of the rod and render unnecessary any other mounting connection between 50 that end of the rod and the bag.

The present improvements further include certain modifications in the construction of the device which more particularly aim at simplifying the manufacture thereof.

Other features of these improvements will be

discussed in the description which follows of the appended drawings, which serve to illustrate how the improvements can be carried into effect.

In the drawings:

Fig. 1 is an exploded view of a spiking device 5 incorporating many of the present improvements;

Fig. 2 shows the lower part of the spiking device in section, and attached to a bag bottom.

Fig. 3 is a view of the mouth of a bag pre-formed with a separator strap; showing how the spiking 10 device may be adapted thereto by the provision of an attachable ring or loop or the like.

Figs. 4 and 5 show a modified form of adaptor ring or loop.

Fig. 6 is a plan view of the mouth of an oval 15 bag pre-formed with two-separator straps; showing how the spiking device may be adapted thereto.

Fig. 7 is a sectional view of part of the rod and sheath; and Fig. 8 an enlarged sectional view of 20 the mounting connection at the bottom of the bag.

Fig. 9 is a view of an inverted bag bottom showing an aligning stick by which the assemblage of 25 the components at the bottom of the bag can be facilitated.

Figs. 10 and 11 show an improved power-multi- 30 plying tool hereinafter referred to.

In the drawings 1 indicates the spiked rod and 35 2 a sheath within which the spiked end is normally retracted by means of a spring 3 while 4 and 5 indicate a handle for the rod.

Golf bags are now often manufactured with a club separator extending across the mouth of the 35 bag and/or wholly or partially down the inside of the bag.

But the spiking device can be readily adapted to such bags, as for example in the manner indicated in Figs. 3 to 5. Thus 11 is a flexible club 40 separator strap already provided in the bag, and 12 a looped clip which can be readily slid along, and if desired, clamped onto the strap to provide a guiding and steady loop 13 for the upper end of the sliding rod. To allow a standard 45 rod to be extended so as to be of sufficient length to be retained in the loop or guide 13 while the spike is being protruded from the bag to the limit permitted, it is convenient to provide an extension piece 14, adapted to make a screw union at one 50 end with a threaded end of the rod and at the other end with a threaded stem of a detachable handle piece 15. The same effect may of course be ensured by using a longer rod, but the foregoing extension piece facilitates manufacturing 55

the rods in standard form. The hand-grip may be suitably padded if desired.

Figs. 4 and 5 show a form of adaptor ring or loop applicable when the width of the club separator strap 11 is horizontally disposed instead of vertically as in Fig. 3.

Where two separator straps are already secured across the mouth of the bag, as for example, in the oval-mouthed bag depicted in Fig. 6, a guiding or steadyng ring or like 16 may be secured 10 medially between them.

In the previous Patent No. 1,826,216, there is provided the spiked rod with a collar which engaged an abutment formed by screwing a stop 15 member in the top end of the sheath.

It is now possible to dispense with this member and form the abutment as indicated by the numeral 17, in Fig. 7, by spinning over the end of the sheath. The collar is indicated by numeral 20 18, and is preferably sweated on the rod.

It is found that when the collar abuts directly against the abutment, the sudden retraction of the spike sets up a hammering action between the collar and the abutment, and this action is 25 especially objectionable when the abutment is formed by spinning over the end of the sheath, as the tendency is to hammer out the abutment. To overcome this objection, there is provided between the collar 18 and the abutment 17, a spring 30 19, or alternatively an india-rubber buffer or equivalent means to cushion the rebound blow. With endwise stiffened bags such cushioning means, particularly when a fairly long coil spring is used in a comparatively long bag, affords the 35 additional advantage of lessening the extent of initial retraction of the spike within the sheath, and the consequent downward movement necessary is less before the spike engages the turf.

The present improvements further deal with a 40 more effective way of strongly securing the spiking device to the bottom of the bag as shown by Fig. 8. For this purpose there is provided a pair of centrally apertured domed spring discs or washers 20, 21, which are arranged one on either 45 side of the bottom 22 of the bag with their concave surfaces directed towards each other. On the disc 20 on the inside of the bag, which is preferably the larger of the pair, rests the open bottom end of the sheath or casing 2 which is internally screw threaded or has sweated therein 50 a liner 23 in which the thread is cut. Into such threaded end of the sheath is screwed from the outside of the bag through the holes in the discs and a hole previously made in the bottom of the 55 bag an externally threaded flanged ferrule 24 which is preferably diametrically grooved on the face of its flange at 25 to receive a special tool or lever e. g., as shown in Figs. 10 and 11 herein-after described, or spanner by which the ferrule 60 may be threaded tightly into the end of the sheath. By this method a comparatively long threaded ferrule may be used which in being screwed into the sheath flattens the domed spring discs 20, 21 such that these offer considerable 65 resistance to any tendency of the ferrule accidentally to work loose, and thereby a notably strong and secure bottom mounting of the device is realized. The apertures in the discs and the bag bottom and the bore in the ferrule are of a size 70 which permits the spiked rod to pass readily therethrough, the aperture in the outside disc conveniently being shaped to receive the ferrule flange so that this lies flush with the disc when the ferrule is screwed in to its limit.

75 The flange end of the ferrule may be internally

threaded to receive a screw closure plug 26 which when inserted prevents the spike from being unintentionally protruded.

When a liner 23 is sweated into the end of the sheath and threaded, and this is a very convenient method of forming the screw thread in a comparatively thin metal sheath, the inner or upper end 24a of the liner may serve as an abutment for the lower end of the spring 3 after the latter has been pushed past the liner into the 10 sheath, the lowest coil of the spring conveniently being expanded and flattened to bear against the liner.

It is explained in detail in the prior specification how simply the device may be attached to existing bags. It is found that the attachment of the components at the bottom of the bag can be still further facilitated by the provision of a small aligning rod or stick 29, see Fig. 9. In attaching the device the sheath 2 is inverted and a 20 drilled end of the aligning stick is intruded into the end thereof and centered and held in position by the spike tip. The inside domed disc 20 is passed convex face forward over the stick so as to rest on the open end of the sheath. The bag 25 with a hole 28 made in the bottom is then passed over the projecting end of the stick, next the outside disc 21, concave face forward, is passed over the stick, and finally the screwed ferrule 24 is dropped over the stick and screwed into the 30 threaded end of the sheath. The stick is then removed and the ferrule tightened up with the tool e. g., lever 29a or spanner provided for that purpose. This tool conveniently consists of a strip of metal, Figs. 10 and 11, having one end 30 bent 35 over to fit the groove 25 in the ferrule flange. Considerable leverage is afforded by such a tool and a very tight union between the screwed ferrule 24 and the sheath 2 may be effected thereby.

Suitable punches can be provided with the 40 spiking device outfit by which without difficulty the hole in the bottom of the bag, and the holes at the top of the bag which receive the flexible separator or hand-grip connection, may be made, or in the case of a metal bottom and/or rim a 45 suitable bit applicable to a common hand brace may be provided with the outfit.

Wherever possible it is preferable to punch any holes such as those by which in unstiffened bags the handle connection is made with the 50 body of the bag in reinforced parts of the bag material.

The present improvements also include a spiked rod made in one-piece with the handle.

In addition to the advantages hereinbefore 55 enumerated, the present improvements conduce to a notable lessening of the weight of the device, while conserving the ease with which it is handled and operated.

What is claimed is:—

1. In combination with a spiking device comprising a spring-retracted sliding spiked spindle and detachable fastening means for securing the device to an ordinary or standard golf bag or like receptacle, means adapted to be attached to a club separator or separators incorporated in the bag to serve as a guide for the upper end of the sliding spiked spindle, said means comprising a clip portion for attachment to the separator and a loop portion serving as the said 70 guide.

2. A spiking device adapted to be detachably secured to an ordinary or standard golf bag or like receptacle, comprising a spiked spindle, a sheath in which said spindle slides, the lower 75

end of said sheath being screw-threaded, a spring housed in said sheath serving normally to keep the spiked end of said spindle retracted within the sheath, a pair of thrust plates adapted to be secured on the inside and outside respectively of the bottom of the bag, a screw-threaded nut for engaging said sheath and means adapted to be attached to a flexible club separator or sep-

arators across the mouth of the bag to serve as a guide for the upper end of the spiked spindle, said means comprising a clip portion for attachment to the separator and a loop portion serving as the said guide.
